UNITED STATES PATENT OFFICE.

AUGUST MOTSCHENBACHER, OF BROOKLYN, NEW YORK, ASSIGNOR TO L. PLAUT & CO., OF NEW YORK, N. Y., A CORPORATION OF NEW YORK.

SHADE-HOLDING ATTACHMENT.

1,407,876.

Specification of Letters Patent. Patented Feb. 28, 1922.

Application filed October 5, 1920. Serial No. 414,813.

To all whom it may concern:

Be it known that I, AUGUST MOTSCHENBACHER, a citizen of the United States, residing at Brooklyn, in the county of Queens and State of New York, have invented a certain new and useful Improvement in Shade-Holding Attachments, of which the following is a specification.

My invention relates to the lighting fixture art, and has for its object to provide means for firmly and securely retaining a shade within the shade holder, which will at the same time be adjustable so as to be adapted for use with varying sized shades. 10 A further object is to provide such an attachment in a simple, durable and inexpensive construction and which may be easily and quickly operated to insert or remove a shade.

20 My invention consists of certain details of construction hereinafter set forth, pointed out in my claim and illustrated in the accompanying drawing in which—

Fig. 1 is a side elevation showing my improved device.

Fig. 2 is a bottom plan view of the same.

Similar reference numerals refer to similar parts throughout the entire description.

As shown in the drawings, 10 is used to 30 indicate a shade holder of the ordinary bell-shaped type, having a plurality of slots 11 in its depending flange, and near the base thereof. The numeral 12 indicates a spring wire, circular in conformation and of lesser 35 diameter than the inner diameter of the flange, said wire not being of quite sufficient length to complete the circle, one end thereof being secured to a lug 13 which projects through one of the slots 11, its other end 40 being secured to a slotted plate 14. This end also is provided with a lug 15 which projects through one of the slots 11, and other lugs 16 are also secured to the wire and project through other slots 11, all of these slots 45 and engaging lugs being designed to mov-

ably seat the spring, in place within the shade holder. These lugs may be formed, if desired, by bends in the wire 12.

To the slotted plate 14, one end of a lever 17 is removably, or rather adjustably, secured, its outer end being pivotally secured at 18 to an L-shaped lever 19, which is itself rotatably secured to the other end of the wire 12, the outwardly projecting end of the lever 19 projecting through one of the 55 slots 11.

In practical operation the lip of a shade 20 is inserted in the shade holder within the wire 12. The lever 19 is then thrown over contracting the ring around the lip of 60 the shade, the movement of said lever being sufficient to carry the pivotal mounting 18 past the rotatable mounting of the lever to the end of the wire 12, thus firmly clamping the wire to the lip of the shade and 65 locking it in this position.

It is obvious that the slotted plate 14, to which the lever 17 may be removably secured, provides an adjustment for the diameter of my wire holding means, so that 70 it may be lengthened or shortened to fit any desired shade.

Having described my invention what I regard as new and desire to secure by Letters Patent is:

75 A shade holding attachment comprising the combination with a bell-shaped holder of an annulus of spring wire mounted within said holder, a lug which projects through a slot in the wall of the holder to which one 80 end of the wire is secured, a slotted plate to which the other end is secured, a plurality of other lugs mounted in other slots in said holder which movably seat said wires, an L-shaped lever to which said plate 85 is rotatably attached, said lever being rotatably secured to one end of said wire.

In testimony whereof, I have signed the foregoing specification.

AUGUST MOTSCHENBACHER.
